(57) CLAIM

The ornamental design for a wheelbarrow frame, as shown and described.

DESCRIPTION

FIG. 1 is a front perspective view of a wheelbarrow frame showing our new design;

FIG. 2 is a front elevational view thereof;

FIG. 3 is a rear elevational view thereof;

FIG. 4 is an enlarged right side elevational view thereof;

FIG. 5 is a left side elevational view thereof;

FIG. 6 is a reduced scale top plan view thereof; and,

FIG. 7 is a bottom plan view thereof.

The broken line showing of a wheelbarrow and wheel is for illustrative purposes only and forms no part of the claimed design.
